FINGER EXERCISING DEVICE

Henry Scott, New York, N. Y.

Application November 13, 1936, Serial No. 110,602

9 Claims. (Cl. 272—67)

This invention relates to new and useful improvements in finger exercising methods and devices to develop the muscles and the agility of fingers for playing instruments like the piano forte or operating devices like the typewriter.

In accordance with the present invention the naturally least developed finger of one hand is impeded to a certain extent to perform a required movement, and the corresponding finger of the other hand is impeded to a greater extent. Usually, the third finger of the right hand is by nature least able to perform the work it is called upon to do in playing the piano or the like. The third finger of the left hand is, in a right-handed person, even less endowed. By impeding the up-and-down movement of the right third finger during piano playing practice, the muscles of this finger will be rapidly developed so that the natural handicap of this finger will soon be overcome. Similarly, the greater impedance to the movements of the left third finger will, within a short time, develop it to be substantially equal to the right third finger.

In accordance with one embodiment of the invention, a mitten is provided for each hand. For a right-handed person the left mitten is thicker, heavier, or less elastic than the right mitten, so that in practicing, the fingers of the left hand will have to work harder than those of the right hand, and the fingers of both hands will have to work much harder than in the normal playing of the piano. Furthermore, that portion of each mitten against which the third finger strikes is less yielding than the other portions, whereby this finger must in practice work much harder than the other fingers.

In order more fully to explain the nature of my invention a few embodiments thereof will be explained in connection with the drawing, in 40 which:

Figs. 1 and 2 are side elevations of two embodiments of the invention.

As shown in Fig. 1, the covering for impeding the movement of the fingers consists of a mitten 1 of knitted wool or other resilient material. That portion of the mitten with which the tip of the fingers contact when in position to play the piano is divided into panels of varying resiliency. As indicated in the drawing, panel 2 with which the first finger cooperates, is most resilient; i. e., it impedes the up-and-down movement of the finger the least. Panels 3 and 4, with which the second finger and the little finger cooperate, are somewhat less resilient, the resiliency of the two panels being substantially alike, since the nat-

ural agility of these two fingers is usually the same. Panel 5, with which the third and least agile finger cooperates, is the least resilient, so that this finger will, in order to strike the piano keys, have to perform a relatively greater amount of work than the other fingers, and its muscles will thus be developed rapidly enough to bring it to a par with the other fingers.

The variable resiliency of portions of the mitten can be produced in any one of a number of ways. The knitting may be looser at one point than at another, stitches may be dropped or heavier or less resilient yarn used in the knitting of one section than in the other. Also, the relative variations may be changed, the important point being that the finger which is naturally least endowed encounter the greatest obstacle and, therefore, develop the fastest. The covering for the thumb 6 may have any resiliency, since the thumb is usually very strong.

The width of the mitten should preferably be such that when the four fingers are spread into the playing position the panels 2 to 5 will be stretched out so that each finger will encounter and press against the panels.

Fig. 1 shows the mitten for the left hand. For a right-handed person the mitten for the right hand will be like the mitten for the left hand, but each panel will be more resilient than the corresponding panel of the left mitten, since the right-hand fingers are naturally better developed and a greater handicap must be placed on the left hand to bring it up to the development of the right hand.

Fig. 2 illustrates another arrangement to attain the purposes of my invention. As shown in this figure, a covering is provided for each finger; 10 for the first finger, 11 for the second finger; 12 for the third finger, and 14 for the little finger. To these finger covers are fastened bands of resilient material 15 such as knitted wool, rubber or the like. These bands 15 are fastened to a wrist strap 16 by means of adjustable buckles 17. The wrist strap 16 may be fastened around the wrist by means of buttons 18. The bands 15 are held together by means of a strap 19.

In this structure the resiliency of the bands 15 may be varied in the same manner as the resiliency of the panels 2 to 5 are varied, and thus when the fingers are in playing position and the straps 15 are stretched out on the top of the player's hand over the knuckles, as each finger plays it will encounter greater or less resiliency, depending upon the elasticity of its restraining band 15. Also, by means of the buckles 55

17, the player may vary the resilience of the associated band and adjust the device to suit the weaknesses of his hand. Here also, for right-handed persons, the device for the right hand 5 will be adjusted so as to restrain the fingers less than the device for the left hand, and the third finger will be obliged to do the heaviest work.

It will be obvious to those skilled in the art that the invention may be subjected to numerous 10 modifications. In the device shown in Fig. 2, fingers may be left off. For instance, if all of a player's fingers except the third is well developed, then only a restraining device for the third finger will be provided. Also, a device or any part of 15 the device shown in Fig. 2, may be used in conjunction with the mitten shown in Fig. 1. In other words, the mitten of Fig. 1 may be pulled on the hand after the device of Fig. 2 has been attached, and thus the fingers doubly restrained; 20 or any part of the device of Fig. 2 may be provided on the hand of the player before he slips on the mitten. In this case, finger cover 12, for instance, may be sewn inside the mitten 1, and the mitten need not be provided with panels of 25 varying resiliency.

What is claimed is:

1. In a finger exercising device, a covering for one hand at least partly but loosely surrounding the fingers, impedances of different magnitudes 30 to impede the required movements of the fingers, the impedance to the movement of the finger that is naturally least apt being greatest, and a similar covering for the other hand with the impedances impeding to a greater extent the required movements of the fingers.
2. The device defined in claim 1 and in which the covering consists of a mitten covering the tips of the fingers, one portion of which is more yielding than another.
3. A device according to claim 1 and in which the covering consists of a mitten covering the tips of the fingers, and the wall of which differs in resiliency under the different fingers.
4. A device according to claim 1 and in which the impedance in the covering of one hand im- 45

pedes the third finger at its tip to a greater extent than the other fingers, and the impedance in the covering of the other hand impedes the third finger at its tip to a greater extent than the impedance of the third finger of the first mentioned hand. 5

5. In a finger exercising device, means attached to the player for impeding at its tip the required movement of one finger of one hand to a certain extent, and means attached to the 10 player for impeding at its tip the required movement of the corresponding finger of the other hand to a greater extent.

6. The device according to claim 5 and in which the first mentioned means includes means 15 variably to impede at their tips the required movements of the fingers of one hand to a certain extent, and the second mentioned means includes means variably to impede at their tips the movements of the fingers of the second hand to a 20 greater extent.

7. The device according to claim 5 and in which means are provided to vary the resiliency 25 of said means attached to the player at the will of the operator.

8. In a device for exercising the fingers to play the keys of digitally operable mechanisms, a covering for one hand at least partly but loosely surrounding the fingers, impedances of different magnitude to impede at the tips the movement 30 of the fingers towards the keys, the impedance to the movement of the finger that is least apt being greatest, and a similar covering for the other hand with impedances impeding at the tips the movement of the fingers toward the keys to a 35 greater extent.

9. In a device for exercising the fingers to play the keys of digitally operable mechanisms, means attached to the player for impeding at the tip the movement towards the keys of one finger 40 of one hand to a certain extent, and means attached to the player for impeding at the tip the movement towards the keys of the corresponding fingers of the other hand to a greater extent.

HENRY SCOTT. 45
